(57) **CLAIM**

The ornamental design for a container carrier as shown and described.

DESCRIPTION

FIG. 1 is an upper perspective view of the first embodiment of a container carrier showing my new design;
FIG. 2 is a lower perspective view of the container carrier of FIG. 1;

FIG. 3 is a top view of the container carrier of FIG. 1;
FIG. 4 is a bottom view of the container carrier of FIG. 1;
FIG. 5 is an end view of the container carrier of FIG. 1;
FIG. 6 is a side view of the container carrier of FIG. 1;
FIG. 7 is an upper perspective view of the second embodiment of a container carrier showing my new design;
FIG. 8 is a lower perspective view of the container carrier of FIG. 7;
FIG. 9 is a top view of the container carrier of FIG. 7;
FIG. 10 is a bottom view of the container carrier of FIG. 7;
FIG. 11 is an end view of the container carrier of FIGS. 7;
and,
FIG. 12 is a side view of the container carrier of FIG. 7.
The broken line portions of the drawings are included to show unclaimed subject matter and form no part of the claimed design.

1 Claim, 12 Drawing Sheets
